CORE DRILLING APPARATUS

John F. Bozeman, Houston, Tex.

Application March 5, 1936, Serial No. 67,224

18 Claims. (Cl. 255—72)

This invention relates to improvements in core drilling apparatus.

The invention has more particularly to do with well drilling operations and more especially to means for taking out cored samples of the stratum or geological formation at different depths as the drilling operation progresses in oil, gas and other relatively deep wells. The invention principally concerns rotary drills of the tubular stem or pipe string type, in which provision is made for the insertion therein of a core drill which operates, in its lowered position, through an axial bore in the main drill head or tool as provided at the bottom end of the tubular stem or string of piping to which rotation is imparted by the regular rotary driving machine provided on the base of the derrick just above the top of the well hole.

In core drilling operations of the character above described, the core drill is usually operated with its cutting end portion some distance in advance of the outer main drill bit or cutting tool, and, obviously, as the characters of the formations or strata, through which the cutting bits or tools pass, vary considerably in many respects, particularly as to the degree of hardness of the material being drilled through, there are times when the outer or main drill bit or cutting tool cuts relatively faster than the inner core drill element, resulting in serious damage to the latter as well as an imperfect core or one that is not a true specimen of the stratum or formation. To avoid damaging the core drill, provision has been made, in some cases, for yieldability ends wise of the core drill when the latter meets with the resistance of relatively hard material during the drilling operation and the main drill cuts faster than said core drill, as just above pointed out; but, unless some provision is also made to give an indication at the top of or above the well hole, of such happening at the bottom of the well, so as to be readily observed by the operator, in order that the speed of the feed and rotation of the drill stem may be reduced or operation thereof stopped entirely, and thereafter resuming operations with due care and proportionate speed in accordance with the then reasonably known conditions at the bottom of the well hole, the coring operation fails and the core that is obtained is not a true specimen of the stratum or formation.

The present invention has for one of its principal objects to provide for practical yieldability of the core drill and an automatic indication of such occurrence during the drilling operation.

Another important object is to produce a simple, practical and efficient core drilling appliance or tool which is readily placed in the tubular drill stem or rotatable string of drill operating pipe, dropped or lowered into working relation to the main drill bit or cutting tool, and releasably interlocked automatically in such working relation and being also under convenient control from above the well hole.

A further object is to provide simple yet practical means for lowering the core drill into the main drill stem and for readily withdrawing the core drill, at will.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a fragmentary view, in vertical section, of the lower end portion of the drill stem with a main drill bit or tool of the fishtail type applied and a core drill also applied and shown in partially extended but normal drilling position relative to the cutting end of the main drill bit or tool;

Figure 2 is a detailed sectional view of the stop ring element for the core drill, the vertical section of the ring being taken at substantially right angles to that shown in Figure 1;

Figure 3 is a vertical section, in fragmentary illustration, of the portion of the drill stem and contained parts just immediately above the parts shown in Figure 1;

Figure 4 is a view of the character of Figures 1 and 3, showing parts and portions of the drill stem and contained parts next adjacent above the parts and portions shown in Figure 3;

Figure 5 is a view of the character of Figures 1, 3 and 4, showing the parts and portions completing the continuity of the structure above the parts and portions shown in Figure 4;

Figure 6 is a fragmentary longitudinal section of the lower portion of the core drill placing and withdrawing tool, showing the spring clutch element thereof engaged with the drawhead of the core drill;

Figure 7 is an elevational view of the spring slip element of the core drill placing and withdrawing tool detached;

Figure 8 is a fragmentary longitudinal section of the upper portion of the core drill placing and withdrawing tool, and is a continuation of

Figure 6, showing certain parts in an inoperative position for engaging the core drill;

Figure 9 is a longitudinal section of the core drill placing and withdrawing tool, with several intermediate portions broken away, but showing the correlation of certain parts operated to position for releasing the core drill and allowing the latter to remain placed in the main drill bit or cutting tool as shown in Figure 1; and

10 Figure 10 is a fragmentary sectional view of the portion of the core drill in the region of the latching elements, said elements being operated to release the latch member proper from engagement with the slotted locking bushing or tubular latch anchoring element, as it may be termed.

15 Referring now to the drawings, the numeral 1 designates the lowermost section or joint of a tubular drill stem, the end portion of which, as shown, is tapered, as at 2, and screw threaded for attachment of the shank portion 3 of a drill bit or tool 4 which, as shown, is of the fishtail type. In the body portion 5 of the drill bit or tool 4 is an axial bore 6, the lower end portion 7 of which is reduced in diameter, affording an annular shoulder 8, while extending diagonally downwardly and outwardly from the upper part of said bore 6 is a passageway 9 for supplying drilling fluid (termed "mud" in the parlance of the oil fields and other well drilling activities) to the lower portion of one face (the forward face) of the drill wing or blade 4a, and similarly from the opposite side of the bore 6 is provided another passageway 10 for supplying fluid to the corresponding face of the opposite wing or blade 4b, in accordance with the usual practice in well drilling operations.

20 Mounted loosely to slide endwise but held from rotation in the bore 6 of the drill bit or tool 4 is a stop ring or element 11, the lower part of the bore 12 of which is of a diameter slightly larger than the external diameter of the tubular core drill cutter body member 13 (see Figure 1) to be later more fully described. The upper part of the bore of the element 11 is upwardly flared, as at 14, and a tapered or bevelled annular seat portion 14a is provided where the parts 12 and 14 of the bore merge, while diametrically opposite slots 9a and 10a are provided in the upper wall portions of the element 11 to constantly register communicably with said fluid passageways 9 and 10, respectively, of the main drill bit or tool 4. This stop ring or element 11 is yieldably held normally with its upper end in abutting contact with the lower end of the tapered lower portion 2 of the tubular drill stem section or joint 1, by a coiled spring element 15 interposed between the lower end of said element 11 and said annular shoulder 8 of the bore 6.

25 To guide the endwise movement and prevent rotation of the element 11 within the bore 6 of the drill bit or tool 4, said element is provided with a relatively short longitudinal slot 16 in one side thereof, into which is projected the inner end portion 17 of a screw-stud 18 inserted through a transverse screw-threaded opening provided therefor in the body portion 5 of the drill bit or tool 4 (see Figures 1 and 2).

30 The core drilling elements will now be described. As shown, the tubular lower body member 13 of the core drill is provided with an ordinary annular cutting bit or head 19 which is screw-threaded, as at 20, to the lower end portion of said body member 13. The bit or head 19 is provided with an annular series of teeth 21 at

35 its lower end, or, obviously, it may be provided with other cutting portions of any conventional or approved character. Above the cutting portions 21 of the bit or head 19 is formed an annular internal shoulder 22, between which and the adjacent end of the tubular body member 13 is loosely placed a ring member 23 having a series of upwardly extending and inwardly turned spring elements 24, through which the core cut by the bit or head 19 is forced upwardly into the 40 tubular body member 13, or, rather, said member 13 is moved downwardly over the core during the drilling operation. As the formation of the core progresses it is taken into the upper drill body tube 25 which is screw-threaded on the upper 45 end portion of said member 13.

45 Said ring member 23 and spring elements 24 constitute a core retainer and being loosely mounted within the core drill, as shown, said retainer remains rotatively stationary with respect to the core but moves endwise downwardly over the core while the drill elements are rotating and being simultaneously fed downwardly. In the region of the spring elements 24 the core drill body tube 13 is preferably downwardly flared 50 slightly, as at 24a, to accommodate said spring elements and also aid in the entrance of the core as it is forced into said tubular member 13, the latter being increased slightly in internal diameter some distance above said flared portion 24a, 55 as at 24b, which increased diameter continues up through the core drill tubing. The core drill tubular member 25 may be of any desirable or ordinary length, depending upon the length of the core to be taken from the stratum or formation through which the well hole is being drilled and depending also upon the practice adopted in each particular locality of well drilling operations; and, as far as the cutting bit and core retainer are concerned, they may be of any approved type. The present invention, however, comprehends radical improvements in the structure, mounting, operation and control of the core drill, which will now be described.

55 The drill cutter body member 13 is provided with an external annular bevelled shoulder 26 to engage the seat 14a of the stop ring or element 11 when the core drill is dropped or lowered into the drill stem tubing and the main drill bit or tool 4 is in raised position, as it is at this time, 60 with respect to the bottom of the well hole being drilled. The spring supported element 11 affords a cushion for the impact when the shouldered portion 26 of the core drill member 13 strikes said element, either when the core drill is 65 dropped by gravity or when lowered by a lowering tool and cable into the main drill stem. In this connection, a special lowering and withdrawing or, as commonly termed a "fishing tool", to be 70 later more fully described, may be provided.

75 The tubular member 25 is screw-threaded, as at 27, at its upper end portion, to the lower nipple portion 28 of a valved coupling element 29 provided with a ball type check-valve member 30 normally closing the lower bore 31 of said coupling element (see Figure 3). The ball member 30 is limited in its upward unseating movement, by a cross bar 32, while transverse ports 33 are provided just above the valve seat 34, affording 80 communication between the upper bore 35 of the coupling element 29 and the fluid passage space 36 between said core drill tube 25 and the main tubular drill stem 1.

85 Threaded at its lower end portion, as at 37, to 90

the upper nipple portion 38 of the coupling element 29, is a tubular spring case or housing 39 having a reduced and externally screw-headed upper portion 40, provided with an axial bore 41 through which a piston rod or stem 42 is freely slidably fitted. As shown, said piston rod 42 has an integral head 43 at its upper end, said head 43 having a bifurcated or open-ended slotted upper portion 44 for a purpose to be presently more fully explained, while the lower end portion of said rod 42 is slightly reduced in diameter to afford an annular shoulder 45 and said reduced portion being externally screw-threaded to receive a detachable head 46 having a counterpart screw-threaded axial opening therein to fit the threads of said reduced end portion of the rod 42, whereby said head 46 is attached to said rod 42 in a manner similar to an ordinary nut and tightened against said annular shoulder 45.

The upper portion of the piston rod 42 works within the lower end portion of an upper tubular casing or housing 47 which is screw-threaded, as at 48, and attached to the reduced externally screw-threaded portion 40 of the tubular casing or housing member 39, and containing a special latching and controlling means for the operation of the core drill when applied in working relation and in withdrawing it, as will be later more fully set forth.

Interposed in the tubular casing or housing member 39, between the piston head 46 and the end of the upper nipple portion 38 of the coupling element 29, is a coiled spring element 49, and a duplicate of said spring element, as at 50, is interposed in the casing or housing 47, between the upper piston head 43 and the end of the reduced upper end portion 40 of said tubular casing or housing member 39. These spring elements 49 and 50 are shown in their normal supporting condition in Figure 3 of the drawings.

Fitted slidably, with relative looseness, between the bifurcated end portions 44 of the upper piston head 43 is the lower hooked end portion of a latch element 51 having an inclined cam slot 52 through which a cross pin or bar 53 on the portions 44 is slidably fitted. The upper end portion of the latch element 51 is pivoted, as at 54, to the bifurcated lower end portion 55 of a link member 56 having an open-ended longitudinal slot 57 in which a reduced longitudinally elongated extension 58 of a fluid flow controlling and core drill supporting bar 59 is loosely fitted to slide freely therein. The bar extension 58 is provided with an elongated longitudinal slot 60 through which a cross pin or bar 61 on the link member 56 is slidably fitted.

The fluid flow controlling and core drill supporting bar 59 is provided with an enlargement or piston type valve-head 62, the under shoulder portion 63 of which rests normally on the upper end of the tubular member 47 (see Figure 5) while its upper shoulder portion 64 is tapered or bevelled, as at 65, and above which said bar extends, as at 66, for some distance, and being of substantially the same diameter as the main lower portion of the bar 59 below said enlargement or valve-head 62, while the above said portion 66, the bar is further reduced in diameter, as at 67, with a bevelled annular shoulder portion 68 at the base of said portion 67. The extreme upper end portion of the reduced portion 67 is tapered or pointed, as at 69, while just below said portion 69, an annular groove 70 is formed, thereby producing a draw-head 69a for the attachment of a special core drill placing and withdrawing or fish-

ing tool to be presently described. Preferably, as shown, the top and bottom shoulders 71, 72, respectively of the groove 70 are bevelled.

For convenience in constructing and assembling the several correlated parts of the main drill stem 5 tube or pipe joints with respect to the placing and operating of the core drill therein, the lowermost main drill stem section 1 preferably terminates with its upper end portion 1a in the region of the normally positioned link member 56 and it is, 10 as customary in the practice, provided with an upwardly flared internally screw-threaded socket in which is received the correspondingly tapered screw-threaded reduced end portion 1b of an upper stem section or pipe joint 1c, which latter terminates with its upper end portion in the region of the draw-head 69a of the core drill bar member 59 and is there provided with a screw-threaded socket 1d for the reception of the reduced screw-threaded end portion 1e of the next adjoining upper drill stem tube or pipe joint, indicated by the reference character 1f, and provided at its upper end portion with an attaching socket 1g, 20 similar to those hereinabove described, it being obvious that additional drill stem tubes or pipe joints are added to the string in the well hole in accordance with the usual practice as the drilling operation progresses.

Fitted as a packing gland in a bore 73 in the upper portion of the drill stem section 1c is a pair 30 of abutting ring members 74, 75, the meeting end portions of which, as shown, are bevelled annularly for the reception of a rubber or other suitable packing ring 76 in the substantially V-shape 35 annular groove thus provided, whereby to make a water-tight seal between the circumferences of said rings 74, 75 and the cylindrical face of the bore 73. As shown, said ring members 74, 75, are tightened between the annular shoulder 76a at the bottom of the bore 73 and the end of the reduced portion 1e of the drill stem section 1f.

The bore 77 of the ring members 74, 75, as thus jointly assembled in the bore 73, is substantially the same as the diameter of the valve-head 62, or in other words, the respective diameters of said 45 parts are such that the valve-head 62 will work in the bore 77 with an easy sliding fit and yet effectively seal the passageway through said bore 77 when said valve-head is moved into it, so as to 50 stop the flow and circulation of the fluid, or "mud" as it is more commonly termed in the well drilling operations, as will be later more fully described.

To afford an easy entrance of the valve-head 62 into the bore 77 of the packing ring members 55 74, 75, the lower end portion of the bore in the lower ring member 75 is preferably bevelled, as at 78, to function with the bevelled shoulder 65 of said valve-head 62. In this connection it is preferable to correspondingly bevel the upper ring member 74, as at 78a, so that said ring members 74 and 75 may be interchangeable.

Fitted in an enlargement of the main bore of the lower drill stem tube or pipe joint 1, near the upper socket portion 1a thereof, is a longitudinally 65 slotted latch anchor tube or cylindrical tubular cage-like element, designated generally by the numeral 79. The generally enlarged portion of the bore of the drill stem section 1 is shown more clearly in Figures 3 and 4 of the drawings and designated by the numeral 80. As shown, said element 79 is provided with a series of upper slots or openings 81 annularly thereof and a similar series of openings near the bottom thereof, as 70 75 at 82.

Between said slots or openings 81, 82, are a multiplicity of larger longitudinally elongated slots or openings 83. In the core drill tubular member 47 there are also provided longitudinal slots 84, 85, the slot 84 being relatively longer than the slot 85 to permit considerable endwise movement of the latch member 51 therein.

The slots or openings 81, 82, are provided in the latch anchor tube 79 primarily for the passage of the drilling fluid or "mud" while the slots 83 are provided primarily for the engagement of the hooked end portion of the latch member 51, whereby to provide an interlocking effect, so that, under certain conditions and in relative positions 10 of the correlated parts, the core drill is rotated by and with the main drill stem tube or string of piping, and at the same time the latch member 51 is interlocked against endwise movement in one direction with respect to said main drill stem but 15 permitted limited movement endwise in the opposite direction.

The upper and lower portions of the main drill stem bore enlargement 80 are reduced in diameter, as at 86 and 87, respectively, to substantially 20 the same diameter of the adjacent end portions 88 and 89 of the latch anchor tube or element 79 which are fitted therein. The lower end portion 89 of said element 79, as shown, is provided with an open-ended slot 90 which fits over the 25 protruding inner end portion of a stud 91 which is inserted in a transverse bore 92 provided therefor in the drill stem tube or pipe joint 1 (see Figure 3) and secured in place, preferably by a welding flux filling in a tapered recess at the outer end portion of said bore 92, as at 93. This provision 30 is to facilitate the placing of the anchoring element 79 and for holding it against rotation independently of the drill stem section 1. In order to also key the upper portion 88 of said element 35 79 against rotation independently of said drill stem section 1 and further relieve said multi-slotted element 79 of torsion a longitudinal key pin or dowel-like pin 94 is placed in a longitudinal bore provided half and half in the contiguous portions 40 of said drill stem section and the portion 88 of said element 79, as shown in Figure 4 of the drawings.

The latch anchor element 79 is held against 45 endwise movement away from the shoulder 95 at the bottom of the portion 87 of the bore enlargement 80, by the abutting end face 96 of the coupling portion 1^b of the upper drill stem section 1^c which is inserted in the socket portion 1^a of said drill stem section 1. This is clearly shown by 50 reading the upper part of Figure 3 together with the lower part of Figure 4 as an upward continuation of Figure 3.

The core drill operation and control will now be 55 described.

In accordance with the usual practice, when the core drill is to be applied, the operation of the main drill is stopped for the time being and the drill stem tube or pipe string is raised to bring the drill bit or cutting tool up some distance from the bottom of the well hole thus far drilled, varying from several inches to a few feet, and the string of drill stem tubing or piping is held in such raised position in the rotary machine at the top of the well hole by the application of the usual slips or retaining elements generally employed for the purpose.

After the driving sector, or "grief joint" or "kelley" as said section is more commonly termed, is removed from the drill stem string, the core drilling appliance, with all of its parts assembled,

is either lowered by a special tool or cable or dropped by its own weight into the drill stem tubing or piping, more generally in the latter way in many well drilling operations. In this connection it may be here noted that in practically all deep well drilling operations the hereinbefore described fluid or "mud" is maintained in the well hole and kept in circulation during the time the drill is operating to clear the drill bit or cutter element of the detritus resulting from the operation of the tool and also to prevent caving of the well hole as well as settling and packing of the detritus at the bottom of the hole. It is, therefore, understood that this fluid or "mud" is in the well hole and the main drill stem tubing when 10 the core drill is lowered or dropped into said tubing, and that the circulation of the fluid or "mud" may or may not be stopped temporarily for the relatively short period during which the core drill is being initially placed in working relation to the main drill bit or cutting tool at the bottom of the tubular stem or pipe string.

As the main drill bit (the bit 4 in the illustration in the accompanying drawings) is lifted from the bottom of the well hole, as hereinbefore 20 stated, the lower cutting end portion of the core drill will be projected a distance substantially twice that of its normal cutting position ahead of the cutting end of the main drill bit, at which time the annular shoulder 26 of the lower core drill 30 tubular member 13 is resting on the seat portion 14^a of the stop ring 11, which latter, as hereinbefore described, is supported by the spring element 15 and thereby affords a cushion when the drill tube shoulder portion 26 strikes said seat 35 portion 14^a of the stop ring 11, as the spring element 15 yields and in which action the counter bevelling of the shoulder 26 and seat 14^a function to centralize the tube 13 and stop element 11 so as to appreciably prevent and overcome any 40 tendency for the element 11 to become canted and bind in the bore 6 of the main drill bit body 5.

As the core drill is lowered or dropped into the main drill stem tubing or pipe string the hooked lower end portion of the latch member 51, by 45 reason of its lower inclined face, indicated at 51^a, together with the co-action of the inclined slot 52 thereof and the guide pin or cross bar 53 of the bifurcated portion 44 of the piston head 43, said latch member 51 is swung back out of 50 anchor tube engaging position and moved relatively endwise, as shown in Figure 10 of the drawings. Then, as the core drill is moved beyond its normal drilling projection with respect to the end of the main drill bit or cutter 4, said 55 latch member 51 has reached a position down in the anchor tube or cage member 79 where the hooked end 51^b of the latch member is below the horizontal plane of the upper ends of said slots or openings 83 of said anchor tube or cage member, whereupon the hook portion of said latch member is free to enter any one of said slots or openings 83 as said latch member 51, together with the connected parts above it, drop by their own combined weight and the pressure of the 65 fluid or the mud in the drill stem tubing or pipe string of the main drill above them.

The parts being in the relative positions just above noted, if the drill stem 1 is rotated and the hooked end portion 51^b of the latch member 51 is projected into the slot or opening 83, the core drill is, obviously, rotated therewith.

To start the drilling operation the main drill stem is lowered and after the core drill has begun to cut the core the main drill bit is gradually 75

socket, is a spring slip element 115, having a transverse open-ended slot 116 at its upper end through which is placed a transverse bar or cross member 117, riveted at its opposite ends in the 5 tubular member 110, whereby said spring slip element 115 is held against rotation in said member 110, but permitted limited endwise movement.

As shown, the slip element 115, which is tubular, is provided with a multiplicity of longitudinal slots 118, thereby producing a series of spring tongue portions 119. The lower end portion of the bore 120 of said slip element 115 is reduced in diameter, as at 121, and provided with 10 internal screw-threads 122, the undersides of which are bevelled and the upper sides of which are substantially horizontal or square, so as to receive, with endwise snap effect, the counterpart upper end portion 123 of a longitudinally 15 movable bar or plunger member 124, the extreme end portion of which is tapered or pointed, as at 125, to enter said threaded bore portion 122, and having external threads 126 below said tapered or pointed end portion and extending to an adjacent 20 bevelled shoulder 127 at the base of said end portion 123 of the bar.

Some distance downward from the upper end of the bar or plunger member 124 it is provided with an annular external shoulder or collar portion 128, between the upper side of which and a screw-collar 129 threaded on the adjacent portion of said bar 124 is a packing ring 130 of rubber or other suitable material compressible against the adjacent inner face of said tubular 25 member 97 (see Figure 6).

Sleeved around said bar or plunger member 124 and interposed between the end of the lower nipple extension 106 of the coupling element 105 and said screw-collar 129 is a coiled spring element 131 which normally acts to press said bar or plunger member 124 downwardly.

The bar or plunger member 124 is externally screw-threaded, as at 132, just below said annular collar portion 128 thereof, and to said threaded portion is attached the upper portion 133 of a spring slip element 134. Said slip element 134, which is shown in detail and detached in Figure 7, is tubular, as shown more clearly in Figure 6, and provided with a series of longitudinal slots 135, thereby producing a series of spring tongue member 136.

The lower end of said bar or plunger member 124 is formed with a tapered recess or socket 137 which is a substantial counterpart of the tapered 55 end portion 69 of the draw-head 69^a of the core drill, and the spring slip element 134 has its lower end portion extended downwardly beyond said socketed end portion 137 of said bar or plunger member 124, and being externally bevelled annularly, as at 138, to engage said bevelled shoulder portion 101 of the tubular member 97 and against which shoulder portion 101 said end portion 138 of the slip element is normally pressed by said spring element 131, the effect of which 60 is to wedge the internal bevelled shoulder portions 139 into the annular groove 70 and engaging relation to the under side of the shoulder portion 71 of the draw-head 69^a of the core drill (see Figure 6).

In the socket 137 of the bar or plunger member 124 are transverse grooves 140 communicating with an axial bore of relatively small diameter in said bar or plunger member, said axial bore, designated by the numeral 141, communicating at its upper end with the bore of the

tubular member 97, at a point above said screw-collar member 129 through a transverse port 142. These grooves 140, bore 141, and port 142, are provided to relieve the compression of fluid in the bores of said tubular members 97 and 110 between the screw-collar member 129 and the end 114^a of the bore 110 of the socket member 110 when the fishing or withdrawing tool is dropped to engage the core drill; and, by contact of the lower end of the bar or plunger member 124 with the draw-head 69^a, said bar or plunger is moved upwardly and thereby compresses said spring element 131, which latter functions as a cushion and said cushioning effect is augmented by the displacement of the fluid in the bores of said 15 tubular members 97 and 110 through said port 142, restricted axial bore 141 and said grooves 140, thereby functioning with the effect of a shock-checking dash pot.

The spring slip element 134, as before stated, 20 is yieldably held by the spring element 131 in normal wedging contact with said shoulder portion 101 of the tubular member 97, and as the fishing tool or withdrawing and core drill placing tool, as it may be termed, is lowered or dropped 25 with momentum into the drill stem tubing or pipe string, and the socketed end portion 137 of the bar or plunger member 124 strikes the draw-head 69^a of the core drill, the tubular member 97 continues on downwardly while the spring element 30 131 yields sufficiently to permit such downward movement a distance so that the bevelled shoulder portion 101 of said tubular member 97 is far enough below the lower end of the spring slip element 134 to permit spreading of the internally 35 shouldered portions 138 thereof over the draw-head 69^a, whereby they snap into the annular groove 70. Then, as the spring element 131 reacts to lift said tubular member 97, the lower end portion of said spring slip member 134 comes in 40 contact with said bevelled shoulder 101 and the internal shoulder portions of the slip element 134 are wedged in interlocking relation under said shoulder portion 71 of the draw-head 69^a of the 45 core drill.

With the several parts in the correlated positions and engaging relation as shown in Figures 6 and 8, if the cable 113 is pulled upwardly the core drill is thereby withdrawn, because, in the meantime, the main drill stem tubing or pipe 50 string has been raised preparatory to the application of the fishing or withdrawing tool. When the bar 59, at the upper end of which the draw-head 69^a is provided, is lifted, the lower end 60^a of the slotted portion 60 of the bar extension 58 first engages the cross bar 61, whereupon the link member 56 is lifted, thereby lifting the latch member 54; and the shoulder at the upper end of the slot 83 in the latch anchor tube or cage-like member 79 being then raised to a position 60 somewhat above the hook of said latch member, the slotted portion 52 of the latch member rides on the cross-bar 53 on the bifurcated portions 44 of the piston head 43, whereby the latch member is cammed and swung back to clear said shoulder upper portion of the slot 83 and is then free to be further lifted through the instrumentality of the connected elements above it; and, by reason of the lower end of the slot 52 coming in contact with said cross-bar 53, the piston stem 70 or rod 42 is pulled up with the latch member 54 and, of course, the entire core drilling tool structure is withdrawn.

In the event the core drill should stick from any cause, or become "frozen", as it is commonly 75

further lowered to the cutting position; that is to say, after the core drill cutter portion 19 has cut a sufficient length of the core for said cutter portion to be in its normal cutting position ahead 5 of the main drill bit 4 as shown in Figure 1 of the drawings. Then, as long as the core cutter and the main drill bit cutting ends remain in this working relation, the drilling operation may continue uninterruptedly until the length of the 10 core is completed. However, should the main drill bit cut faster than the core drill bit or cutter portion, the core drill tubing will yield upwardly, or, rather, with the same effect, it will be that the main drill stem moves downwardly with respect to said core drill tubing, and by reason of 15 the hooked portion 51^b of the latch member 51 being engaged under the upper end of the slot or opening 63 of the anchor tube or cage member 19, and the slot 85 of the tube member 47 of the 20 core drill assembly being entirely above the lower end of said latch member 51, and also that the upper end of the slot 52 is in engagement with the cross bar 53 of the bifurcated portion 44 of the piston head 43, said head 43 and the lower 25 head 46 connected thereto by the stem or rod 42, are obviously moved downwardly with the main drill stem 1, or, putting it the other way around, the core drill tubing 47 moves upwardly with respect to said elements, 43, 42 and 46, whereupon 30 said upper spring element 50 is compressed between said upper head 43 and the opposed end portion 40 of the tubular casing or housing member 39, and simultaneously therewith the lower spring element 49 is compressed between said 35 lower head 46 and the end of the opposed nipple extension 38 of the check-valved coupling element 29.

It is here noted that the compound springs 49, 50, are a very important feature of the invention, as such are provided in order to attain the requisite normal spring pressure and reactive effect within limited longitudinal range or dimensions. In this connection the compounding of the spring elements may be further multiplied. 45 The above noted relative movement of the parts is also permitted because of the provision of the longitudinal slot 60 in the reduced lower end portion 58 of the fluid valve controlling and core drill supporting bar 59 with which the cross bar 50 61 of the slotted portion of the link member 56 cooperates. This provision permits of the upper end of the tubular member 47 bearing normally against the bottom shoulder 63 of the valve-head 62, whereby to push said valve-head 62 up into 55 the bore 71 of the packing gland rings 14, 15 of the main drill stem section 1.

As soon as the valve head 62 enters, even slightly, into said bore 71 of the ring members 14, 15, the flow of the drilling fluid or mud through said 60 bore 71 is stopped and thereby the back pressure in the drill stem tubing or pipe string above said valve-head 62 retards the action of the drilling fluid or mud pump, and possibly stopping the operation of the pump entirely, depending upon 65 the type of pump used; and, anyway, giving an appreciable indication to the operator that core drill has yielded and caused the cessation in the flow and circulation of the drilling fluid or mud; or, in some cases, such occurrence may be obviously indicated by a pressure gage as is sometimes used in the fluid or mud circulating system. 70

Obviously, as soon as the operator notices that the core drill has yielded, with the effect as above indicated, it is only necessary to raise the main 75

drill stem tubing or pipe string to lift the main drill bit from the bottom of the well hole or retard the downward feed of said main drill stem until the core drill again is in its normal drilling position with respect to the cutting end of the main drill bit, to which position the core drill is moved by the re-action of said spring elements 49, 50, whereupon the valve-head 62 is either withdrawn from said bore 71 of the ring members 14, 15, by the weight of the parts attached above 10 said valve-head and the bar member 59 below it, or augmented by the fluid or mud pressure from above. 5

To release the fluid or mud from the tubular members 13 and 25 as the formed core is moved 15 up into said members, the hereinbefore described ball check-valve 39 is provided, so that when unseated, the fluid or mud passes out through the ports 33 in the coupling element 29 into the annular space 36 between the core drill tubing 20 and the main drill stem tube 1. In this connection it may be here noted that said ball check valve 39 has a further important function in normally preventing entrance of the circulating fluid or mud downwardly into the tubes 25 and 13 and 25 washing away the formed core therein.

After the core is completed the core drill is removed from the main drill stem by means of a special "fishing" or core drill withdrawing tool to be now described, which tool is also adapted 30 for lowering the core drill into the main drill stem, in some operations, instead of dropping the core drill by its own weight, as hereinbefore stated.

Said fishing or withdrawing and core drill 35 lowering tool is illustrated in Figures 6, 7, 8 and 9 of the drawings, the lower core drill engaging portions of the tool being shown in Figure 6 and the upper portions in Figure 8. As shown, said tool comprises a lower main tubular member 97, 40 the lowermost bore portion 98 of which is of a diameter to fit slidably over the stem portion 66 of the core drill. At the top of the bore portion 98 is an internal annular shoulder 99, having a bevelled underface 100 which is a counterpart 45 of the bevelled shoulder 68 at the upper end of the stem portion 66 of the core drill, and a bevelled upper face 101 above which the bore 102 is enlarged to a diameter somewhat larger than the bore 98. 50

The bore 102 is reduced slightly in diameter, as at 103, beginning with an annular internal shoulder 104 and extending up to a coupling element 105, said coupling element having a screw-threaded lower nipple portion 106 to which the upper 55 end portion of said tubular member is attached, as at 107. The upper nipple extension 108 of said coupling element 105 is externally screw-threaded, as at 109, for the attachment of the tubular lower end portion 110 of an elongated 60 draw-bar or rod 111, commonly termed a "sinker bar" because it is utilized as a weight in lowering the tool into the drill stem tubing or pipe string, and varying in length in actual practice from approximately four to six feet. However, said bar 65 is not of any restricted length except, of course, within certain limits for convenience in handling the tool in placing it in the drill stem tubing and withdrawing it therefrom.

At the upper end of the bar 111 is provided an 70 ordinary socket member 112 to which the lower end of the cable 113 is attached securely in any usual or approved manner.

Fitted loosely in the tubular member 110, the bore 114 of which constitutes, in effect, a slip 75

termed, in the main drill stem, so as not to be drawn out by the cable and fishing tool as just above described, provision is made for the release of the fishing tool from the draw-head of the core 5 drill. To this end, in practice, the cable 113 is passed through a suitable or approved stuffing box or packing element, not shown, but obvious, placed on or in the upper end portion of the main drill stem tube or pipe string at the top of or 10 above the well hole and provision is made for pumping the fluid or mud, hereinbefore described in connection with the drilling operation, in which event hydraulic pressure is set up in the drill stem above the fishing tool, whereupon, if the 15 cable 113 is let down or slackened with respect to the engaged fishing tool which it would otherwise be tending to lift up, the pressure of the fluid or mud on the top shoulder 110^a of the tubular portion 110 of the sinker bar 112, as well as upon 20 the shoulder 112^a at the top of the cable attaching socket 112 and the outer surface of the tubular member 97, will force the fishing tool downwardly until the lower end 97^a of said tubular member 25 97 comes in contact with the annular shoulder 64 at the top of the valve-head 62, which latter is resting with its bottom shoulder 63 on the upper end of the tubular member 47 of the core drill.

As the fishing tool moves downwardly under the pressure of the fluid or mud, as just above 30 described, the spring slip element 115 comes in contact with the upper end portion 125 of the plunger member 124 and by reason of the provision of the cross bar 117 and the slotted portion 35 116 of said slip element 115, said element is raised in the bore 114 of the socket member 110 until the upper end of said slip element is arrested against the end 114^a of the bore 114, immediately upon the happening of which, the pointed and externally screw-threaded end portion 125, 126, 40 of the plunger member 124 is forced into the screw-threaded reduced lower end bore portion 122 of said spring slip member or element 115 with a sudden snap effect because the bevelled internal annular shoulder portion 108^a of the upper 45 per extension 108 of the coupling member 105 is at the time located a sufficient distance below the externally bevelled lower end portion 115^a of the spring slip element 115, so that the tongue members 119 are free to spread as the counterpart 50 screw-threaded portions 122 and 126 ride into engagement with each other and become interlocked against endwise separation until released in a manner to be presently described.

With the several parts positioned and interlocked as just above described, and as shown in Figure 9 of the drawings, the internal annular shoulder 101 of the tubular member 97 is positioned a considerable distance below the bevelled end portion 138 of the spring slip element 134. 55 Now, if the cable 113 is pulled upwardly under power, the tubular member 97 is lifted with the sinker bar 112 through the connection of the coupling element 105 and the slip socket tubular member 110, and the bevelled lower end 115^a of the spring slip element 115 becomes seated and wedged in the counterpart seat afforded by the bevelled shoulder portion 108^a of the nipple portion 108 of said coupling element 105, whereby 60 said tongue portions 119 of the spring slip element 115 are securely held against release from the screw-threaded end portion 123 of the plunger member 124. Then, as the tongue members 136 of the spring slip element 134 are unrestrained from outward movement, the internal shoulder 65 portions 139 thereof are spread out of engage- 70

ment from under the shoulder 71 of the draw-head and the fishing or withdrawing tool is withdrawn, leaving the core drill in the main drill stem tubing or pipe string.

When the fishing or withdrawing tool is withdrawn, the plunger member 124 is released from the spring slip element 115 by unscrewing the engaged end portion 123 from the screw-threaded end portion 121 of the spring slip element by applying a key-tool with a blade similar to a 10 screw-driver to the grooved portions 140 in the tapered end socket 137 of the plunger member 124, which is readily accomplished by inserting the key-tool in through the lower end portion of the tubular member 97. 15

In cases where the core drill is lowered into the main drill stem tubing or pipe string by the withdrawing and lowering tool of the invention herein described, the lower end portion of the tool (the tubular portion 97 thereof) is placed 20 over the upper end portions 67, 66, of the core drill, with the spring slip element 134 engaged with the draw-head 69^a; and, after the core drill is lowered into its working relation to the main drill bit or cutter element 4, the lowering 25 tool is released by the same process as that followed in releasing the tool from the stuck or frozen core drill, as hereinabove described. That is to say, the hydraulic pressure is set up in the 30 drill stem tubing to effect the engagement of the plunger member 124 with the spring slip element 115, after which the cable is pulled upwardly, withdrawing the lowering tool from the core drill, whereby said core drill by its own weight and the 35 fluid pressure in the lower portion of the surrounding drill stem tubing is held with sufficient resistance for the release of the spring slip tongue members 136 from the draw-head 69^a.

Obviously, the general structure and arrangements of the assembled apparatus, as well as the 40 details of the several component parts thereof, may be changed or modified in many respects within the spirit and scope of the invention as defined in the appended claims. The invention, 45 therefore, is not limited to the specific construction and arrangements shown in the accompanying illustrative drawings.

What I claim and desire to secure by Letters Patent, is:

1. In combination with a main tubular drill stem having a drill bit or cutting tool at the lower end thereof, said bit or cutting tool having an axial bore therethrough, a core drill insertable in said drill stem and movable operably 55 in and through the bore of said main drill bit or cutting tool, means for releasably interlocking said core drill to said main tubular drill stem to be rotated by and with said stem and having provision for limited endwise movement of the 60 core drill in the region of its rotatably interlocked working position in said main tubular drill stem and bit or cutting tool, means for yieldably pressing the core drill in normal cutting position with its cutting end portion in advance of the main bit or cutting tool, and means for indicating to the operator the yielding of the 65 core drill from its normally advanced drilling position.

2. In combination with a main tubular drill 70 stem having a drill bit or cutting tool at its lower end, said bit or tool having an axial bore therethrough, a core drill insertable in said drill stem and movable operably in and through the bore 75 of said main drill bit or cutting tool, means for

- engaging said core drill with said main drill stem whereby to rotate said core drill by said main drill stem, but permitting endwise movement of the core drill in said stem and through said main 5 drill bit or cutting tool, means for yieldably pressing said core drill endwise into normal cutting position with its cutting end in advance of said main drill bit or tool, and means on said core drill for closing the bore of said main drill 10 stem and stopping the flow of the fluid in said stem upon the yielding of the core drill from its normally advanced drilling position with respect to said main drill bit or cutting tool.
3. The combination as set forth in claim 2, 15 and the fluid-flow-stopping means on the core drill comprising a valve-head portion movable slidably endwise into a portion of the main drill stem bore thereabove of a diameter substantially the same as the diameter of the valve-head.
4. In combination with a rotary drilling tube and fixed cutting bit at the lower end thereof, a core cutting tube fitted with a core retainer and so constructed that it will travel from the surface down through the rotary drilling tube, to 20 an automatic anchorage in its core cutting position and being removable upwardly through the rotary drilling tube to the surface, means for projecting said core cutting tube with its cutting end portion ahead of the drill bit of the rotary drilling tube, means for circulating drilling fluid down through said rotary drilling tube and around the core cutting tube, means operable between the core cutting tube and rotary drilling tube to block circulation of the drilling fluid 25 when the core cutting tube yields upwardly from normally projected core cutting position, whereby to indicate such occurrence to the operator.
5. In combination with a tubular rotary drill stem through which a core drill may be dropped or lowered and also removed upwardly therethrough by means of a cable tool, a fixed drill bit carried by the drill stem and having an axial bore of larger diameter than the lower end portion of the core drill but smaller than the upper 30 portion of the core drill, providing an upper facing shoulder on which rests a spring supporting a stop ring, said stop ring having side fluid openings communicably registering with fluid passages in the main drill bit, said stop ring having a reduced lower bore portion below said side fluid openings affording an internal annular stop shoulder for the core drill, said stop ring locked to rotate with said main drill bit but movable endwise therein, said annular shoulder of the 35 stop ring receiving in contact an external annular shoulder on the core drill and the stop ring yielding downward and acting as a shock absorber by compressing the supporting spring therebelow when the core drill is dropped or lowered into working position with relation to the main drill bit.
6. In combination with a tubular rotary drill stem, a core drill capable of being dropped or lowered, either by its own weight or by means of a cable tool and also removed upwardly through the drill stem, said core drill in operative position being projected through an axial bore in the main drill bit or cutting tool at the lower end of said drill stem, the core drill having a shouldered external portion above its cutting end portion, the axial bore of the main drill bit having an upper enlarged portion affording an internal annular shoulder, a stop ring slidable endwise in 45 said enlargement of the bore of the main drill bit to receive by supporting contact therewith said

external shouldered portion of the core drill when the latter is dropped or lowered in the tubular main drill stem, and a spring element interposed between said stop ring and said internal annular shoulder of the bore of the main drill bit whereby to yieldably support said stop ring and function with said ring to cushion the impact when the core drill is dropped or lowered in said main drill stem. 5

7. The combination set forth in claim 6, and further describing the main drill bit or cutting tool as provided with fluid passages and said stop ring as provided with constantly communicable openings maintained in registering relation to said fluid passages of the main drill bit 15 or cutting tool whereby to circulate fluid from the main drill stem through said fluid passages of the drill bit or cutting tool, and the axial bore of the drill bit or cutting tool and also the bore of the stop ring being of a diameter sufficiently 20 larger than the diameter of the core drill portions working therethrough, whereby to circulate fluid in the space therebetween.

8. The combination set forth in claim 6, and further describing the core drill as having an 25 interlocking engagement with the main drill stem whereby to be rotated by and with the latter but permitted endwise movement with respect to said main drill stem, means for yieldably pressing the core drill downwardly into normal working 30 position with its cutting end portion projected in advance of the main drill bit or cutting tool, and means on said core drill for closing the bore of the main drill stem and stopping circulation of the fluid therein upon the yielding endwise 35 movement of the core drill upwardly with respect to the main drill bit or cutting tool or the relative downward movement of the main drill stem and its drill bit or cutting tool whereby to lessen the projection of the core drill cutting 40 end portion from its normal working position with respect to the main drill bit.

9. The combination of a tubular main drill stem and a core drill inserted in said main drill stem, means for releasably interlocking said core 45 drill to said main drill stem so as to be rotated by and with the latter but being permitted endwise movement relative to the main drill stem, yieldable means for holding said core drill in normally positioned working relation in said main 50 drill stem, said core drill having a cylindrical valve-head at its upper portion, and the bore of said main drill stem having a replaceable valve-ring into the bore of which said valve head of the core drill slides to close fluid circulation 55 through said main drill stem upon the yielding upwardly of the core drill with respect to the main drill stem or the movement of the main drill stem downwardly with respect to said core 60 drill.

10. The combination set forth in claim 9, and the valve-ring consisting of relatively hardened metal and having packing means for providing a seal against passage of fluid between the ring and the bore of the main drill stem. 65

11. In combination with a rotary drill stem, a fixed drill bit having a central bore, a core barrel provided with a core cutting head at its lower end, said barrel extending through said central bore of the fixed drill bit with the core cutting head 70 extended beyond said fixed drill bit, said core barrel being detachably latched to said rotary drill stem, the latching means comprising a latch member pivotally secured at its upper portion to an upper inner longitudinally movable member, 75

a longitudinally movable core drill supporting bar extended upwardly beyond the upper end of the core barrel and having a longitudinally slideable connection with said first mentioned longitudinally movable member to which the latch member is pivotally attached, the lower end portion of said latch member having a longitudinally operable cam connection with a plunger member, compound spring elements acting upon said plunger member whereby to normally hold said latch member in interlocked engagement with the rotary drill stem and functioning to yieldably hold said core barrel with its core cutting head portion in the normally extended working relation of said head with respect to the fixed drill bit.

12. In a core drill, the combination of a main tubular drill stem having a fixed bit at its lower end, a tubular core drill body inserted in said main drill stem and means for releasably interlocking said core drill tubular body member to rotate with said main drill stem but with relative longitudinal movement between said main drill stem and said core drill tubular body member, said means comprising a latch member having a hooked lower portion engageable with a slotted shoulder portion of the main drill stem, said hooked lower portion of the latch member having a cam slot therein, a plunger member yieldably supported and normally urged upwardly in said tubular core drill body by compound spring elements, said plunger member having a transverse bar member extended through the cam slot of said latch member and cooperating with said cam slot to normally hold said latch member in engagement with said slotted shoulder portion of the main drill stem, a longitudinally movable link member within said core drill tubular body member, the lower end portion of said link member being pivotally attached to the upper end portion of said latch member, and a supporting bar slidably longitudinally in said tubular core drill body and having a longitudinally slotted connection with the upper portion of said link member, said bar extending above said core drill tubular body member and having at its upper end provision for engagement with a lowering and lifting cable tool.

13. In combination, a tubular main drill stem having a centrally bored main bit at its lower end, a tubular core drill body member inserted in said main drill stem and movable longitudinally therein, a core cutting head at the lower end of said core drill tubular body member, a supporting bar movable longitudinally in said tubular body member and projected normally above the upper end of said tubular body member, a link member in said tubular body member having a limited end-wise movable connection between its upper portion and the lower end portion of said supporting bar, a latch member having a hooked lower portion working through a longitudinal slot provided therefor in said tubular body member and being pivotally attached at its upper end portion to the lower portion of said link member, a plunger member having limited end-wise movement in said tubular body member, compound spring elements normally urging said plunger upwardly to its uppermost limit, a sliding cam connection between the upper portion of said plunger member, the main drill stem having an internal shoulder portion under which the hooked portion of the latch member engages by the action of the sliding cam connection with the plunger member and the action of said compound

spring elements whereby to yieldably hold the core drill tubular body member in normal position in the main drill stem with the core cutting head projected to work in advance of the main drill bit.

14. In combination, a main tubular drill stem having a main bit at its lower end, a core drill tubular body member inserted in said tubular drill stem and having a cutting head projected through an axial bore in said main bit to a normal working position in advance of said main bit, a longitudinally slotted anchor tube fitted in said main drill stem in fixed relation thereto as to both rotative and end-wise movement, a supporting bar slidable both longitudinally and rotatively in said core drill tubular body member, the upper portion of said supporting bar being projected normally above said core drill tubular body member, a link member in said core drill tubular body member, the upper portion of said link member having a slot and pin connection with the lower end portion of said supporting bar whereby said link and bar are movable end-wise relative to each other but are keyed against independent rotation, a latch member having its upper portion pivotally attached to the lower portion of said link member, the lower portion of said latch member having a transverse hook extension to enter the longitudinally slotted portions of said anchor tube in said main drill stem, said core drill tubular body member being longitudinally slotted for the movement of the latch member, a plunger member having limited end-wise movement in said core drill tubular body member, a sliding cam connection between the upper portion of said plunger member and the lower portion of said latch member whereby when said plunger member is at the limit of its upward movement said latch member is projected to cooperative engaging relation with said longitudinally slotted anchor tube of said main drill stem, and movement downwardly of said plunger member retracts said latch member from such cooperative relation to said anchor tube, and compound spring elements arranged to normally press said plunger member upwardly to its uppermost limit and effect the actuation of said latch member to its cooperative engaging relation with said anchor tube of the main drill stem, in which relation of the parts the core drill tubular body member is yieldably held in its normal position in said main drill stem.

15. In combination with a tubular main drill stem having a main bit at its lower end, a core drill inserted in said main drill stem, releasable latching means for holding said core drill in its working position in said main drill stem, said core drill having a core cutting head at its lower end projected ahead of the main cutting bit of said main drill stem in the normal position of the parts, said core drill having a supporting bar extending upwardly therefrom and provided with an attached head, a cable supported and actuated lowering and raising tool having a tubular body member, the lower end portion of which is adapted to be fitted over the upper end portion of said supporting bar of the core drill, and a spring slip member in said tubular body member of said raising and lowering tool adapted to engage the head portion of said supporting bar of said core drill, said spring slip element having an upwardly extending plunger bar, and a second spring slip element having limited end-wise movement in said cable supported and actuated tubular member, said second described spring

- slip element and the upper end portion of said plunger member of the lower spring slip element having counterpart screw-threads for interlocking engagement when said second mentioned slip element and said plunger extension are moved in relation to each other as by the upward movement of the plunger member or the downward movement of said tubular body portion of the cable tool.
- 10 16. In combination with a tubular main drill stem and a core drill inserted in said main drill stem, said core drill having an upward supporting bar provided with an engaging head at its upper end, said head having a tapered upper portion and an annular shoulder therebelow, a cable supported and actuated raising and lowering tool comprising a tubular body member fittable over said headed supporting extension of the core drill, said tubular body member of the raising and lowering tool having a bevelled internal annular shoulder, a spring slip element in said tubular body member having tongue members bevelled at their lower ends to engage the bevelled annular seat of said tubular body member of the supporting and actuating body tube, said spring slip element having a depending central extension having an axial bore therethrough, the lower portion of said bore terminating in transverse grooves in a tapered socket at the end thereof for the reception of the tapered headed portion of the supporting bar of the core drill, the upper end portion of said axial bore communicating with the space in said tubular body member of the raising and lowering tool through a transverse port in an upward extension of said spring slip element, the upper portion of said upper extension of said spring slip element having provision for releasable snap engagement with an upper spring slip element provided therefor in said tubular body member of the raising and lowering

tool, whereby said tool may be lowered into the main drill stem with the core drill attached and being releasable from the core drill when lowered into working position in the main drill stem.

17. In combination with a tubular main drill stem, a core drill operable and removable through its entire length by means of a cable lowering and lifting tool, a characteristic cable tool having means for engaging the core drill and having spring and hydraulic shock absorbing means to stop said tool in downward travel and prevent automatic release of tool when lowered into engagement with the core drill, and means for forcing said tool farther down after engagement with the core drill by hydraulic pressure supplied through said tubular main drill stem from above whereby to effect release of said tool.

18. In combination with a detachable rotary core drill insertable in a tubular rotary drill stem and removable by means of a cable tool, the core drill having latch means to hold core drill down and rotate it with the main drill stem when in coring position within rotary drill stem, core drill anchor tube in the main drill stem, means adapted to rigidly secure said core drill anchor tube at each end in the main drill stem at working position of latch on core drill to hold down and rotate the core drill and by-pass a portion of the drilling fluid from around core drill latch through ports in the upper end of anchor tube and down between anchor tube and main drill stem through cavity formed in main drill stem, said fluid returning through ports in anchor tube back around core drill at lower end of anchor tube and bottom of cavity in main drill stem, and means for blocking circulation of fluid above said herein described circulating provision automatically upon the yielding of the core drill from normal drilling position.

JOHN F. BOZEMAN.
